UNITED STATES PATENT OFFICE.

GEORGE CARL VENNUM, OF WILMINGTON, DELAWARE, ASSIGNOR TO EDGE MOOR IRON COMPANY, OF EDGE MOOR, DELAWARE, A CORPORATION OF DELAWARE

BAFFLING FOR WATER-TUBE STEAM BOILERS.

Application filed September 15, 1924. Serial No. 737,751.

My invention relates to the class of water tube steam boilers in which a wide bank of water tubes connected at top and bottom by drums or sectional headers lies directly in the path of the furnace gases and, more particularly, my invention relates to boilers of the type described in my pending application filed July 2, 1921, Serial No. 482,086, Patent No. 1,618,141. The object of my invention is to provide a simple and efficient means by which at the same time a down flow of water is brought about in the rear tubes of the tube bank at points intermediate its ends, and the path of the heating gases is sufficiently contracted as they pass through the tube bank and impart heat thereto, to maintain a proper speed of flow throughout the thickness of the tube bank.

The nature of my improvements will be best understood as described in connection with the drawings in which they are illustrated and in which

Figure 1 is a side elevation of a boiler constructed in general accord with that described in my aforesaid application.

Figure 2 is a horizontal section on the line 2—2 of Fig. 1.

Figure 3, a cross section of the tube bank on the line 3—3 of Fig. 1.

Figure 4 is a view generally similar to Fig. 1, but showing the tube bank united at top and bottom with sectional headers so as to form the tube bank of a series of separable units.

Figure 5 is a cross section on the line 5—5 of Fig. 4, and

Figure 6, a fragmentary view illustrating the construction and mode of uniting the separable headers of the different ends of the boiler.

Figure 7 is a fragmentary front view showing the upper headers of Fig. 4, the tubes and baffle plates.

Figure 8 is a perspective view illustrating the construction of a baffle plate shown in Fig. 3, and

Figure 9 is a perspective view illustrating the construction of the baffle plate shown in Fig. 5.

A is the furnace. B, B, etc., water tubes extending in a wide bank across the top of the furnace and united at top and bottom to headers which may be the drums, as indicated at B', B'', in Fig. 1, or sectional headers as indicated at b' b'' in Fig. 4. C is

the steam and water drum of the boiler united to the upper header or headers by a pipe C' and a lower header or headers by a pipe C''. D, D', indicate the tubes of a superheater connected at their bottom by headers D'', connected at top by a pipe D' with the steam space of the drum C. E indicates the water tubes of the water heating section of the boiler. These are connected in series by means of headers indicated at E' and are connected with the steam and water drum C by a pipe E''. This water heating section of the boiler is made up of progressively shorter rows of tubes enclosed in a contracting flue indicated at E''. At D', D'', I have indicated dampers in the superheater.

G, G, are baffle plates which, as shown in Fig. 3, may extend angularly through the space between some of the rear tubes of the tube bank B, so as to protect certain of the rear tubes from direct contact with the furnace gases, and also so as to form a series of contracted passages through the rear tubes. G', G', in Fig. 5, illustrate an alternative disposition of the baffle plates in which, instead of extending into the space between the rear tubes, the baffle plates are simply located at the rear of the tube bank. In both cases the baffle plates which extend, of course, parallel with the tubes, are symmetrically disposed and in the construction shown in Fig. 5, while groups of the rear tubes are not physically protected from contact with the furnace gases, the flow of the gases through the space between the baffles directly results in the bulk of the gases passing the tubes immediately in front of the baffles with but little or no contact therewith.

It is obvious, of course, that the baffles disposed as described will result in an increased speed of flow of gas through the rear portion of the tube bank and also it will be obvious that the rear groups of tubes protected from contact with or full contact with the gases will serve for the down-flow of water and will cause this down-flow to take place throughout the length of the tube bank, thus greatly relieving the headers into which the tubes open which may be much smaller than where the bulk of the water has to flow through the ends of the headers before it finds a path for down-flow.

Where sectional headers are used, as

shown in Figs. 4, 5 and 6, baffle plates are provided for each of the units consisting of a group of tubes and connecting headers and little or no flow occurs from header to header in either direction. I have provided nipples at b^3 to permit such flow as may occur.

Having now described my invention, what I claim as new, and desire to secure by Letters Patent, is:

1. In combination with a steam boiler having substantially straight top and bottom headers connected by a wide and deep bank of water tubes extending across a single pass for furnace gases, means for contracting the flow of gases through the tube bank and for promoting downflow of water in spaced groups of tubes at the rear of the bank, said groups being located intermediate the ends of the bank, said means consisting of a plurality of spaced baffle plates extending parallel to the tubes at the rear of the tube bank substantially throughout the length of the tubes some of said baffle plates being located intermediate the ends of the tube bank and being of such breadth and

so disposed as to extend over groups of three or more tubes and keep some of them out of the path of the furnace gases.

2. In combination with a steam boiler 30 having a substantially straight wide and deep bank of water tubes extending across a single pass for furnace gases and made up of connected units each unit comprising an upper and lower sectional header connected by a tube bank, said headers being connected together laterally by conduits of restricted area, means for contracting the flow of gases through the wide tube bank and for promoting down flow of water through rear 40 tubes of each sectional unit consisting of baffle plates of less width than the tube bank of the unit extending parallel to the tubes at the rear of each unit and substantially throughout the length of said tubes said 45 baffle plates being of such width as to extend over groups of three or more of said rear tubes so as to keep some of the rear tubes of each unit out of the path of the heating gases.

GEORGE CARL VENNUM.
